UNITED STATES PATENT OFFICE.

TIMOTHY HAWKES AND LEWIS A. HAWKES, OF JERSEY CITY, N. J.

FOUNTAIN ATTACHMENT FOR PENS.

SPECIFICATION forming part of Letters Patent No. 275,825, dated April 17, 1883.

Application filed November 13, 1882. (No model.)

To all whom it may concern:

Be it known that we, TIMOTHY HAWKES and LEWIS A. HAWKES, of Jersey City, Hudson county, State of New Jersey, have invented 5 an Improvement in Fountain Attachments for Pens, of which the following description, in connection with the accompanying drawings, is a specification, like letters on the drawings representing like parts.

10 Our invention relates to a fountain attachment for pens, by which a common pen in a common pen-holder is enabled to take up a large amount of ink, when dipped, so that a considerable number of lines may be written 15 at each dipping of the pen.

The attachment consists essentially of a metallic hood or cover inclosing a space between it and the back of the pen, the said hood being provided with a loop or socket fitted to embrace the shank portion of the pen that enters the usual pen-holder, the said hood thus being held securely in proper position relative to the pen. The hood is so shaped that the space or ink-reservoir between it and 20 the pen gradually increases in depth from the point toward the shank portion of the pen, thus insuring the largest possible space or reservoir for ink consistent with a proper capillary holding power, and also causing the ink 25 to flow by capillary attraction toward the point of the pen instead of away therefrom. A very large amount of ink is thus held with great security, there being less danger of a drop of ink falling from the pen than is the 30 case with an ordinary pen not provided with a fountain attachment.

Fountain attachments have been heretofore devised consisting of various forms of receptacles for ink or fingers extending over the 40 front or back of the pen and attached to the said pen or pen-holder in various ways; and we do not broadly claim an attachment for increasing the quantity of ink that can be held by capillary attachment upon a pen; nor do 45 we claim a slide or collar adjustable upon the shank of a pen for securing a fountain attachment to such pen, which fountain attachment is integral with said slide or collar.

Figure 1 is a longitudinal section of a pen 50 provided with a fountain attachment embodying this invention; Fig. 2 a side elevation

thereof; Fig. 3, an under side view thereof; Fig. 4, a transverse section of the pen and its attachment on line x x , Fig. 3; Fig. 5, a similar section on line y y , Fig. 2; and Fig. 6, an 55 end view of the loop or socket portion of the attachment.

The pen a may be of any of the forms that are commonly manufactured and sold.

The fountain attachment consists of a hood 60 or cover, b , shaped to correspond with the particular style of pen upon which it is intended to be used, there being in general terms, as many different forms of attachment as there are essentially different shaped pens, and it 65 not being attempted, as heretofore, to produce an attachment that will work equally well with any kind of pen. The hood b is shaped to almost completely inclose the pen a , there being thus formed a chamber or reservoir, c , between 70 the back of the pen and the inside of the hood. The edges 2 of the hood are nearly parallel with the edges of the pen, as best shown in Fig. 3, the space being so small as to cause the ink to be securely held by capillary attraction. The middle portion of the hood between its edges 2, is arched up above the back of the pen, the space between the hood and pen increasing from the point toward the shank portion d of the pen, as shown by Figs. 75 1, 4, and 5, the latter showing the maximum size of the chamber c near the shank of the pen. By this construction a very large reservoir is afforded, while there is no danger of the ink escaping, and the ink naturally trav- 80 85 els toward the point portion of the pen.

It will be seen that when the reservoir attachment is constructed, as herein described, with especial reference to the shape of the pen, it is essential that it should be held 90 securely in a definite position with relation to the pen, so that the space or opening between the edge 2 of the hood and the edge of the pen may remain uniform and equal on each side of the pen.

The proper holding of the hood upon the pen is insured by its holding-socket e , made as a sleeve fitted to completely surround and embrace the shank portion d of the pen, it being slipped over the said shank and remaining 100 just below the portion that is inserted in the pen-holder.

One of the especial features of this invention consists in making the attachment to correspond with the particular style of pen with which it is to be used, instead of attempting to make one that will operate with any pen, such latter attachments usually holding a much smaller amount of ink, and that with less security, so that the ink is likely to be shaken off and fall upon the paper.

10 We claim—

The hood *b*, provided with the reservoir *c* and collar *e*, and having its edges 2 to fit sub-

stantially parallel with the edges of the pen, and constituting a fountain attachment for pens, as set forth.

In testimony whereof we have signed our names to this specification in the presence of two subscribing witnesses.

TIMOTHY HAWKES.
LEWIS A. HAWKES.
